CLAIM

The ornamental design for a paintball gun body, as shown and described.

DESCRIPTION

This application is related to U.S. Patent application Ser. No. 10/695,049, entitled "Electro-Pneumatic Paintball Gun," filed Oct. 27, 2003.

FIG. 1 is a perspective view of a paintball gun body, showing my new design in full lines, with the broken lines showing environmental association matter for illustration purposes only;

FIG. 2 is a top plan view thereof;

FIG. 3 is a rear elevational view thereof;

FIG. 4 is a front elevational view thereof;

FIG. 5 is a left side, elevational view thereof.

FIG. 6 is a right side, elevational view thereof; and,

FIG. 7 is a bottom plan view thereof.

The broken lines are for illustrative purposes only and form no part of the claimed design.
